CLAIM

The ornamental design for a fire pit table, as shown and described.

DESCRIPTION

FIG. 1 is a side-top perspective view of a fire pit table showing my new design;

FIG. 2 is a front elevational view of the fire pit table shown in FIG. 1;

FIG. 3 is a rear elevational view of the fire pit table shown in FIG. 1;

FIG. 4 is a left side elevational view of the fire pit table shown in FIG. 1;

FIG. 5 is a right side elevational view of the fire pit table shown in FIG. 1;

FIG. 6 is a top plan view of the fire pit table shown in FIG. 1;

FIG. 7 is a bottom plan view of the fire pit table shown in FIG. 1; and,

FIG. 8 is a bottom-side perspective view of the fire pit table shown in FIG. 1.

The broken lines shown in the drawings are for the purpose of illustrating portions of the fire pit table and form no part of the claimed design.

1 Claim, 5 Drawing Sheets
